[57] CLAIM

The ornamental design for a blister package for a reel,
as shown and described.

DESCRIPTION

FIG. 1 is a top plan view of a blister package for a reel
showing our new design;

FIG. 2 is a bottom plan view thereof;

FIG. 3 is a front elevational view thereof;

FIG. 4 is a rear elevational view thereof;

FIG. 5 is a left side elevational view thereof, the right
side view being a mirror image thereof;

FIG. 6 is an enlarged sectional view thereof, partially
broken away, taken along the lines 6—6 of FIG. 1.

FIG. 2.

FIG. 1.
6+FIG. 3.
6+FIG. 4.

FIG. 6.

FIG. 5.
